UNITED STATES PATENT OFFICE.

JOHN H. WARE, JR., OF OXFORD, PENNSYLVANIA.

APPARATUS FOR ERECTING POLES.

Application filed January 9, 1923. Serial No. 611,629.

To all whom it may concern:

Be it known that I, JOHN H. WARE, Jr., a citizen of the United States, residing at Oxford, in the county of Chester and State of Pennsylvania, have invented a new and useful Apparatus for Erecting Poles, of which the following is a specification.

The present invention relates to improvements in apparatus for use in digging holes and erecting telephone, telegraph, trolley, transmission line and like poles and which apparatus is mounted upon a truck or tractor and is therefore portable.

Objects of the present invention are to provide for digging or boring the post-holes in alignment even though the location of the post-holes be comparatively inaccessible or remote from the road way and even though the ground be sloping or uneven; to provide improved means for crowding or feeding the auger that bores or digs the holes even when the auger is spaced at a considerable distance from the truck or tractor, for example, in order to bore or dig holes in locations such as are last above referred to; to provide for the satisfactory application of the power of the plant of the truck or tractor to the work of drilling the post-holes and erecting the poles; to provide equipment for putting the poles in vertical position in the holes and holding the poles in such position while the space around them in the holes is filled by means of mechanical equipment and without the use of pikes and the like; and, generally, to provide portable equipment which shall be simple in construction, operable from the power plant of the truck or tractor, if desired, capable of satisfactorily digging post-holes in the position desired, and adapted to get the poles into vertical position in the holes and to hold them in that position whilst the holes are filled, it being of course understood that some or all of these objects may be omitted.

The invention will be claimed at the end hereof but will be first described in connection with the embodiment of it selected from other embodiments for the sake of illustration in the accompanying drawings forming part hereof and in which—

Figure 1 is a side view of portable apparatus for use in the erection of poles which embodies features of the invention.

Fig. 2 is a view looking in the direction 55 of the arrow 2 in Fig. 1.

Fig. 3 is a view looking from left to right in Fig. 1 and with parts omitted for the sake of clearness.

Fig. 4 is a detached view, partly in section, and drawn to an enlarged scale and showing a feature of construction illustrated to the left in Fig. 3.

Fig. 5 is a section taken on the line 5—5 of Fig. 3.

Fig. 6 is a partial plan, somewhat in section, of the rear portion of the tractor, and

Fig. 7 is a rear view illustrating a modification.

The invention will be first described in 70 application to a Fordson tractor but it must be borne in mind that the invention is not limited to that kind of a truck or tractor nor to the utilization of the power plant of the truck or tractor although such utilization possesses advantages.

In the drawings 1 is a generally rectangular frame mounted on the tractor or truck, generally indicated at 3. Rising from the frame are standards 4 shown to comprise members joined at their tops and mounted on the edges of the frame 1. A T-frame is pivoted to the standards 4 as at 5, and this frame may be turned about the pivot 5 by means of a screw jack 6 interposed between its head 7 and the frame 1. The jack is operated in both directions and is shown as lengthened and shortened by a hand chain 8 and nut 9 which is driven from the hand chain by the bevel gears 10. 80 Mounted on the T-frame is a tripod of which the shear legs 11 and 12 are pivoted to the head 7 of the T-frame and of which the leg 13 is extended and contracted and is pivoted to the shank 14 of the T-frame. The leg 13 is shown as extended and contracted by means of a screw 15 turntable by means of gearing 16 mounted in a housing 17 and driven by an air motor 18 to which air is supplied from a tank 19 mounted in the standards 4. The housing 17 serves to take end thrust in two directions and is pivoted to the member 14. 20 is an extensible and contractable arm or boom and it is pivoted to the rear standard 4 by means of bracket 21, Fig. 5, having a pivot 22 for motion in a vertical plane and a pivot 23 for motion in a horizontal plane. The boom or arm 20

is lengthened and shortened by a screw 24 having a head mounted in a housing 25, and this screw is turned, as shown, by means of a chain 26 and toothed wheel 27. At its free 5 end the boom is forked or otherwise arranged to support a motor 28 supplied with air and adapted to turn the auger 29. At the top of the tripod are pivoted claws 30 connected by cables 31 which pass over 10 sheaves 32 and then over a pulley 33. These cables 31 are connected to a cable 34 which passes through the arm 13 over a guide pulley 35 to a winch 36. 37 is an air compressor driven by a chain 38 from a pulley 39 actuated by the power plant of the Fordson 15 tractor and which pulley or the shaft on which it is mounted is a usual provision of a Fordson tractor. At the rear of the Fordson tractor is applied an extension, Fig. 6, 20 which includes a worm wheel 40, drums 41 and 42, clutches 43 for connecting the worm wheel and either of the drums, a worm 44, and a clutch 45 by which the worm 44 may be connected with and disconnected from 25 the worm shaft 46 of the Fordson tractor. 47 are clutches for connecting and disconnecting the driving wheels 48 and the worm wheel 49 driven by the worm 50 to propel the Fordson tractor. 51 is a cable passing 30 over one of the pulleys 52 at the top of the tripod and hawled in and let out by the drum 42. 53 is a cable taken in and let out by the drum 41.

The operation and mode of use of the described apparatus may be explained as follows:

The tripod may be put into vertical position by shortening the leg 13 by means of the screw connection 15 and motor 18, or 40 even permitted to occupy the position shown in Fig. 1. The arm or boom 20 with the auger gear 28 detached can be swung around the pivot 23 parallel with the frame and under the tripod with its free end projecting 45 forward. The clutch 45 being disconnected and the clutches 47 connected, the tractor or motor truck can be driven to the place where the poles are to be erected and can be used to pull a trailer upon which the poles are 50 loaded. Having arrived at the place where the poles are to be erected the various parts are brought into the position substantially shown in Fig. 1 with the auger on the line along which the spaced poles are to be arranged. For this purpose the point of suspension of the cable 51 at the apex of the tripod can be placed over the center of the proposed posthole approximately by positioning the truck and accurately by adjusting 55 the leg 13 and the arm 20. The auger is then rotated by the motor 28 and crowded downward by the cable 53 whilst the cable 51 is slackened off and the length of the arm 20 is adjusted to preserve the alignment of 60 the auger. In order to utilize the power 65

plant of the tractor for working the cable the clutches 47 are disconnected and the clutch 45 is connected. Upon the completion of the hole a cable passed over one of the sheaves 52 and operated by one of the drums is attached to a pole and the latter is hoisted into more or less vertical position with its butt in the hole. By this operation the upper part of the pole is brought between the claws 30 which are closed as by the cable 70 34 in such a way that they grasp the pole which is diagrammatically indicated by the dotted line *a* in Fig. 2, thus the butt of the pole rests in the hole and the upper part of the pole is connected with the tripod. The 75 pole is brought into and held in vertical position by adjustment of the leg 13 of the tripod and by adjustment of the jack 6 and as these two adjustments are at right angles in respect to each other the pole can be accurately positioned and held until the space 80 between the butt of the pole and the wall of the hole is filled and rammed.

From the foregoing description, it appears that there is provided a derrick having at its top pole grasping means and a hoist for positioning the pole with respect to the grasping means and that this derrick is equipped with adjustments operable in two planes whereby the pole can be aligned or placed vertically and held in that position. It is also evident that means are provided for suspending the auger mechanism over the place where the hole is to be dug and that in connection with such means there is a down draft cable or chain for feeding or crowding the auger into the ground.

The construction and mode of operation of the modification shown in Fig. 7, are as described above except as follows: Instead of a Fordson tractor use is made of a truck 3^a and the tripod is made adjustable crosswise of the truck by the provision of screw means 15^a for adjusting the length of one of its shear legs 11^a, its leg 13^a being also adjustable as above described. The legs of the tripod are connected with the truck by suitable articulations 5^a in the nature of universal joints.

It will be obvious to those skilled in the art to which the invention relates that modifications may be made in details of construction, arrangement and form of embodiment without departing from the spirit of the invention which is not limited as to those matters or otherwise than as the prior art and the appended claims may require.

I claim:

1. Apparatus for digging post holes comprising in combination a truck, a pivotal arm projecting from the truck, auger mechanism carried at the free end of the arm, an overhead cable for vertically supporting the free end of the arm, a second cable for 125

- pulling down on the free end of the arm, means for lengthening and shortening the arm to preserve auger alignment, and devices for letting out the first mentioned cable as the other cable is drawn in to crowd the auger.
2. Apparatus for digging post holes comprising in combination a truck, auger mechanism spaced from the truck, and an arm projecting from the truck connection between the arm and auger mechanism and cable means, operatable to crowd the auger downward.
- 10 3. Apparatus for digging post holes comprising in combination a truck, auger mechanism, an arm projecting from the truck for co-operating in applying down draft to the auger mechanism, a cable extending upward and adapted to pull down on the auger mechanism, and means for operating 20 the cable.
4. Apparatus for digging post holes comprising in combination a truck, a tripod mounted on the truck and of which one leg is extensible and contractible to position 25 the apex at different distances from the truck, a pivotal arm projecting from the truck and provided with means for adjusting its length to align its free end in respect to the apex of the tripod, auger mechanism 30 at the free end of the arm, a cable for suspending the auger mechanism from the apex of the tripod, a cable for pulling down on the auger mechanism, and means for operating the parts.

JOHN H. WARE, JR.
